Application July 26, 1946, Serial No. 686,488

12 Claims. (Cl. 219—47)

1

This invention relates to dispensing, vending and heating apparatus in general. More particularly, this invention relates to check and/or time controlled high frequency electrical heating devices for vending or dispensing apparatus.

An object of this invention is to provide an arrangement for popping corn through the use of radio frequency currents.

Another object of this invention is to provide an apparatus employing electrode means in the nature of capacitor electrodes which are energized or charged by high frequency electric current and between which are supported kernels of popcorn for the popping thereof.

Another object of this invention is to provide a check and time control for high frequency electrical heating apparatus.

Another object of this invention is to provide a high frequency electrical heating apparatus for vending and/or dispensing machines of the type vending and/or dispensing edible products that it is desirable to heat prior to consumption.

A further object of this invention is to provide an electrical heating apparatus control for a vending or dispensing machine of a type adapted to vend or dispense an edible product such as popcorn immediately after it is popped or heated in a sealed package.

Still another object of this invention is to provide a dispensing or vending apparatus for receiving a plurality of sealed packages of edible products such as popcorn and for vending or dispensing such products in the original sealed package.

Still a further object of this invention relates to a control circuit for electrically heating and dispensing edible products in the original packages while hot without opening and resealing the original packages or damaging such packages.

A still further object of this invention is to provide an electrical heating and dispensing apparatus for heating and dispensing edible products such as popcorn in individual packages without the necessity of opening and resealing such packages once they have been placed in the heating and dispensing apparatus.

Another object of this invention is to provide an electrical apparatus for popping corn packaged in individual packages and dispensing the corn in such packages immediately after it is popped.

Other and further objects of this invention will be apparent to those skilled in the art to which this invention relates from the following specification and the claims.

I have found that high frequency electric cur-

2

rents may be efficiently employed in the popping of corn primarily because the greatest heating action produced by the high frequency currents is concentrated in the interior of the popcorn kernel. In other words, the interior of the corn kernel becomes heated and the water vapor therein causes the kernel to explode without the skin of the kernel being impaired by heating action prior to the popping of the kernel. Furthermore, employing high frequency current for popping corn increases the efficiency and rapidity with which the corn is popped because of this concentrated heating action. In accordance with this invention, I have provided a high frequency capacitor electrode arrangement between which the kernels of popcorn are supported preferably in a single layer. A high frequency oscillation generator is connected to these capacitor electrodes and this supplies the high frequency current for heating the popcorn kernels. The heating action in the popcorn kernels is in the nature of a dielectric loss which takes place in the kernel inasmuch as the kernel is in the nature of a dielectric and this loss is proportional to the dielectric constant of the inside of the popcorn kernel and the frequency of the high frequency oscillations supplied to the capacitor electrodes. Consequently by varying or controlling the frequency of the high frequency oscillation generator the time required for popping the corn may be controlled, that is, the time may in general be reduced by increasing the frequency of the high frequency oscillations. Furthermore, the corn kernels may be impregnated with a suitable oil or other liquid if it is desired to increase the dielectric constant of the interior of the corn kernel. This would of course also cause the corn kernels to pop faster since the dielectric losses therein would be increased thereby.

Other features of this invention will be set forth in detail in the following specification, claims and the drawings.

Referring to the drawings briefly:

Fig. 1 is a view showing structural details and a schematic wiring diagram of the electrical circuit employed in my invention; Fig. 2 is a schematic wiring diagram of the high frequency current generator adapted to be employed in my invention; Fig. 3 is a detail view of the motor control relay employed in this invention; Figs. 3a and 3b are detail views of the leverage employed to trip the mercury switch of the motor control relay shown in Fig. 3; Fig. 4 is a vertical sectional view of the coin trip mechanism and electromagnetic interlock employed therewith in ac-

cordance with this invention; Fig. 5 is a sectional view taken along the line 5—5 of Fig. 4; Fig. 6 is a sectional view taken along the line 6—6 of Fig. 4; Fig. 7 is an end view of the motor driven conveyor employed in this invention; Fig. 7a is a fragmentary side view of one of the conveyor supporting and actuating drums; Fig. 7b is a plan view of the conveyor, top electrode structure and popcorn bag bin; Fig. 8 is a detail view of a thermal switch employed in a modified form of this invention; and Fig. 9 is a detail view of the high frequency electrodes with a bag of popped popcorn therebetween, and the contactor associated with the top electrode; and Fig. 10 is a view of the cabinet partially cut away to show mounting of some of the apparatus inside.

Referring to the drawing in detail, reference numeral 10 designates a plug of conventional design adapted to be inserted into a conventional wall receptacle connected to a 110 volt alternating current lighting or power circuit. A pair of conductors 14 and 15 are attached to the conductors 12 and 13, respectively, and these former conductors are connected to terminals 16 and 17, respectively, of the high frequency current generator 18. The terminals 16 and 17 are connected to the primary of the high frequency generator filament or cathode power transformer, as will be more particularly set forth, so that when the plug 10 is connected to a supply of 110 volt alternating current and the switch 11 is closed the power transformer of the generator 18 is energized and the filaments of the generator tubes are heated to electron emissive temperature.

The conductor 12 is also connected to the contact 19 of the contactor K, supported by the arm 25 of insulation or other suitable material. The other contact 20 of the contactor K is supported by an insulation element 20a, as is illustrated in the vertical sectional view shown in Fig. 3, and is connected through the conductor 26 to the terminal 27 of the high-frequency-generator-plate-circuit controller D. The other terminal 28 of the winding of the controller D is connected through the conductor 29 to the terminal 30 of the winding C of the coin-closed-circuit interlock and the other terminal 31 of this winding C is connected to the contact 32 of this interlock circuit. The contact 32 is supported by insulation attached to the coin slot, as will be described in connection with Figs. 4 and 5. The contact 33 of the interlock circuit is connected to the 110 volt circuit conductor 13 through the wire 34.

Furthermore, the wire 12 is also connected to the terminal 21 of the winding I, the other terminal 22 of this winding I being connected through the conductor 35 to the contact 36 of the contactor H. The other contact 37 of this contactor H is connected to the conductor 38 and thence to the conductor 13. The details of construction of the contactor H are illustrated in Fig. 9, and they are described in the description of this figure.

Still further, the wire 12 is connected to the terminal 23 of the mercury switch J, the terminal 24 of this switch is connected to the terminal 40 of the motor 39 and the other terminal 41 of the motor is connected to the conductor 13. The details of construction and mounting of the mercury switch and associated devices are illustrated in Figs. 3, 3a and 3b. The wire 12 is connected to one side of the 110 volt A. C. plug 10 through the switch 11 and the other side of this plug 10 is connected to one side of the winding 50 of the electromagnetic shutter arrangement. This elec-

tromagnetic shutter arrangement is provided with an armature 51 associated with the winding 50 and mechanically connected to a coin diverting member or scoop 52 which reaches into the coin receiving chute of this apparatus and diverts the coins from the coin slot when the circuit of the apparatus is not at least partially energized, for example, when the switch 11 is open or when the plug 10 is not inserted into the current carrying receptacle. This will be described in detail in the operation of the apparatus.

Referring to Fig. 2 in detail, the primary winding of the transformer 60 is connected to the terminals 16 and 17 which correspond to the terminals 16 and 17 of Fig. 1, and which are connected to the lines 12 and 13 adapted to be associated with a 110 volt lighting circuit or similar power circuit. The secondary of the transformer 60 is connected to the cathodes of the electric discharge devices 61 and 62. Each of these devices is provided with a cathode, a grid electrode and an anode, the grid electrode being positioned between the cathode and the anode. The cathodes of the electric discharge devices 61 and 62 are permanently connected to the secondary of the transformer 60 and these cathodes are heated to electron emissive temperature when the plug 10 is operatively associated with a suitable power line and the switch 11 is closed. A second transformer 63 having a primary winding and a secondary winding is employed for energizing the anodes of the devices 61 and 62 and the primary of this transformer 63 is also connected to the terminals 16 and 17 to be energized from the lines 12 and 13; however, in this case this transformer is not energized immediately upon the closing of the switch 11, but its operation is dependent upon the closing of the contacts E of the relay D, these contacts E being connected across the terminals 64 and 65, as shown in Fig. 1, said terminals corresponding to like designated terminals in Fig. 2. When the contacts E of relay D are closed and the transformer 63 is energized, a relatively high voltage is applied alternately from the halves of the secondary of this transformer across the anode-cathode discharge space of the devices 61 and 62. The anodes of the devices 61 and 62 are coupled through condensers 66 and 67, respectively, to a terminal of an oscillatory or tank circuit 68. The other terminal of this tank circuit is coupled through condenser 70 to the grids of the discharge devices 61 and 62. The grids of these discharge devices 61 and 62 are connected together through a suitable potentiometer for balancing purposes, and the variable contact of this potentiometer is connected to the condenser 70 and to the grid resistor 70a, which functions as a suitable conductive circuit back to the center tap of the filament transformer secondary. This center tap is bypassed for high frequency currents to the outer terminals by suitable condensers, and the common connection of these condensers is connected to the terminal 69 of the inductance of the tank circuit 68. High frequency currents are derived from the tank circuit 68 through suitable connections employing the coupling condensers 71 and 72 which are connected to the terminals 73 and 74, respectively. These terminals 73 and 74 are also shown on Fig. 1 where terminal 73 is connected by the conductor 75 to the high frequency brush contactor 77, shown in detail in Fig. 7a. Terminal 74 is connected by a conductor 76 to the high frequency electrode F, which is shown in detail in Fig. 9.

Referring to Figs. 3 and 3a, these figures illustrate details of the electromagnetically and mechanically controlled mercury switch J and the contactor K. The mercury switch J is held on the member 86 by a metal strap 86a hugging portions of the top and sides of the casing of said switch. These casings are usually made of glass or similar insulation material however they may be made partially of metal and partially of insulation. If the casing is of metal a suitable insulation sleeve must be positioned between this metal and the strap 86a as well as between it and the metal of the member 86. The member 86 may of course be practically entirely of insulation material, such as "Bakelite" and a small metal, that is, iron, armature 86b attached to the bottom thereof so that the member 86 may be electromagnetically actuated by the solenoid I. This solenoid is provided with an iron core 86c around which the winding 86d of the solenoid is positioned and from which said winding is insulated. The core 86c is provided with a threaded hole for receiving the flat headed bolt 86e and fastening the solenoid assembly to the bottom of the housing 86f. The wires 12 and 35 leading to the winding of the solenoid I enter the housing 86f through suitable insulation bushings or sleeves 21a and 22a respectively. Likewise the wire 26 connected to the contact 20 passes through the insulation bushing 26a in a side wall of the housing 86f and the wire connected to the terminal 24 of the mercury switch J passes through the insulation bushing 24a into the housing. On the other hand the terminal 23 of the mercury switch J and the terminal 21 of the solenoid are connected to the contact 19 inside of the housing and therefore no bushings are required for these wires.

The member 86 supporting the mercury switch J and the contact 19 of the switch K, is pivoted at 93 and is rotatable through a limited angle about this point. The pivot 93 is supported by the housing 86f and supports the popcorn bag receiving-scoop-shaped member 92 on the ends thereof externally of the aforesaid housing as shown in the side view Fig. 3a and top view Fig. 3b.

In Figs. 4, 5 and 6 are illustrated details of construction of coin tripped electromagnetic switch arrangement, the contact 32 and 33 supporting members 32a and 33a of which are attached to the coin chute 80 by bolts 80b which are insulated from the members 32a and 33a by insulation spacers 80a. The members 32a and 33a are also insulated from each other except when the member 33a is depressed by a coin 91 so that the contacts 32 and 33 are in engagement. When the member 33a is depressed by a coin 91 the armature 33b is positioned in the air gap between the pole faces of the core 33c of the magnetic device C as shown in dotted outline in Fig. 6. When this apparatus is in normal working order the member 33a is held in this depressed position shown in dotted outline in Fig. 6 until the bag of popcorn 84 in position under the high frequency electrode F expands to popped condition and the switch or contactor K is opened so that the winding C is de-energized as more fully described under the portion of this specification dealing with the operation of this apparatus.

Referring now to Figs. 7 and 7a wherein details of the conveyor 81 supporting drum 83 and some of the associated devices are shown, it will be observed that the high frequency current con-

ducting brush 71, connected to the oscillator 18 by the wire 75, is urged by the spring 71a into frictional contact with the drum 83. The drum 83 is a metallic tube supported in the bearings 83g and 83d by the shaft 83b and the spokes 83a, the latter being preferably of insulation material so that high frequency current fed to the drum 83 and from this drum to the flexible conveyor 81, also of conducting material, is not conducted to the shaft 83b. The shaft 83b is provided with a pulley 83e or other suitable driving element coupled to the motor 39 shown in Fig. 1.

Fig. 8 is a top view of the high frequency electrode F, illustrating a modified form of this apparatus employing a thermal relay consisting of a thermally responsive bi-metallic element 101 for closing the contacts 103 and 104 of the contactor Ha in place of the contactor H shown in Fig. 1. The bi-metallic element 101 is anchored to the base of the thermal switch at one end by the bolt 102 and the other end carrying the contact 104 is movable toward the contact 103 which is fastened to the switch base also. The switch unit is placed partially in the high frequency electric field existing in the region surrounding the electrode F and the adjacent parts of the conveyor 81 so that the bi-metallic element 101 is heated by the high frequency electric currents set up therein and caused to expand, that is, the contact 104 is caused to gradually move up to and engage contact 103 because the strips making up the bi-metallic member 101 are of different materials and have different thermal coefficients of expansion. The time interval required for this expansion may be adjusted as by properly positioning this switch in the field so that this time interval will correspond to the time required to pop the corn in the electric field.

The contacts 103 and 104 are connected to the terminals 37a and 36a respectively and these correspond to the terminals 37 and 36 respectively of Fig. 1 so that it will be apparent that the switch Ha may be used in place of the switch H of Fig. 1.

Fig. 9 is a detail side view of the high frequency electrode F, the electrode support G and the contactor H. The electrode F is a thin sheet of copper encased in insulation 105 of "Bakelite" or the like to give it mechanical strength and to insulate it and to reduce corona losses from the sharp edges and corners. This electrode is supported by the metal tube G when a fresh bag of corn 84 is pushed out of the bin or reservoir 85 by the conveyor 81 and one of the transverse laths 81a attached to the conveyor 81. As the corn pops through the application of the high frequency field thereto, as more fully explained in the description of the operation of this invention, the electrode F is raised and the tubular element G slides up through the insulation support 106. The tubular element G raises the insulation button shaped member 112, which is fastened to the end of the element G and limits the downward movement of the element G, upward, carrying the contact 111 of the contactor H fastened to the button 112 upward also, into engagement with the contact 110 of the contactor H. This condition of contact between the contacts 110 and 111 is achieved when the corn 84 is fully popped and expanded. The gap between the contacts 110 and 111 may be changed either increased or decreased by the adjusting knob 108 which is employed for rotating the threaded member supporting the contact 110 in the thread-

ed metallic support 107. This support is fastened to the insulation bracket 109 which is attached to the insulator 106.

The operation of this invention will now be described. As was previously stated, when the connector plug 10 is connected to a suitable power circuit and the switch 11 is manually closed the primary of the filament heating transformer 60 (shown in Fig. 2) is energized and the filaments or cathodes of the electric discharge devices or tubes 61 and 62 are heated to electron-emissive temperature. The winding 50 of the electromagnetic shutter is energized by the current flowing through the primary of the transformer 60 and the coin diverting shutter 52 is lifted by the magnetic armature 51 of the winding 50, out of the coin slot 80 so that a coin 91 dropping through the coin slot may move unobstructed down said coin slot and engage the resilient member A, depressing this member downwards sufficiently to close the contacts 32—33 of the contactor B. Closing the contactor B energizes the electromagnetic lock C which holds the resilient member A in depressed position. The current flowing through the winding C also flows through the conductor 29, the winding D and the contactor K, the contacts 19 and 20 of which are closed, completing the circuit to the conductor 12. Energizing the winding D functions to close the contacts E and this connects the primary of the transformer 63 (Fig. 2) to the power circuit lines 12 and 13, thus energizing the electric discharge devices 61 and 62 so as to cause these devices to generate high frequency electrical oscillations, the frequency of said oscillations being determined by the electrical tuning of the tank circuit 63. This electrical tuning may be varied or controlled by adjusting either the capacity or the inductance or both of this tank circuit, and for optimum cornpopping results this frequency should be adjusted somewhere in the neighborhood between 30 and 100 megacycles per second. Of course, other frequencies may be selected with less efficiency. The high frequency currents are fed through the coupling condensers 71 and 72 and conductors 75 and 76 to the popcorn conveyor 81 and the electrode F. This conveyor 81 may be made of woven copper wire in the form of a copper screen. The conveyor is an endless belt supported by a pair of rotatable drums 82 and 83, the drum 83 being in the form of a metallic cylinder suitable for conducting the high frequency current, fed to it by the brush 77, to the electrically conducting conveyor belt 81. When high frequency current is fed to the conducting belt 81 and the electrode F from the oscillation generator 18 by means of the conductors 75 and 76, respectively, the popcorn inside of the bag 84, resting on the conveyor 81 directly beneath the electrode F, is subjected to the high frequency current and is popped. This popping causes the bag 84 to expand considerably and raise the electrode F with the result that the contacts 110 and 111 (Fig. 9) of the contactor H engage each other and close the circuit to the solenoid I. When the solenoid I is energized, it functions to open the circuit between the contacts 19 and 20 of the contactor K and at the same time closes the circuit of the mercury switch J since this mercury switch is mounted upon the pivoted armature 86 associated with the solenoid I, shown in Figs. 1 and 3. Closing the circuit of the mercury switch J operates to energize the motor 39 from the power circuit and at the same time the contacts 19 and 20 are opened, thus deenergizing the winding of the relay D. The contacts E

of the relay D are opened and the anode circuit of the oscillation generator tubes 61 and 62 is de-energized. When the motor 39 is energized, it functions to move the conveyor 81 a sufficient distance so that the bag of popped corn is dumped from the conveyor over the drum 83 into a suitable chute from which the customer that inserted the coin 91 into the coin slot 80, may extract the popped corn. When the bag of popped corn is dumped over the drum 83, it engages the pan-shaped lever 92, shown in detail in Figs. 3a and 3b, which is associated with the pivot 93 of the mercury switch J and contactor K. The bag of popped corn thus opens this mercury switch and closes the contactor K so that the circuit of the motor 39 is de-energized. At the same time as the bag of popped corn was dumped from the conveyor by the operation of the motor 39, another bag of corn was moved into position underneath the suspended electrode F, from the reservoir 85.

The resetting of the contactor K to its closed position by the bag of popped corn dumped from the conveyor conditioned this apparatus for popping the next bag of corn. It will be observed that when the circuit of the contactor K was opened by energizing the solenoid I through the closing of the contactor H, the solenoid D and the solenoid C were both de-energized so that the anode circuit of the high frequency generator tubes 61 and 62 was de-energized and the coin actuated resilient member A was released to its normal position.

Furthermore when the apparatus is initially loaded with bags of popcorn to be popped the motor 39 may be connected to the power circuit with the manual switch 120 which is arranged to short the mercury switch J, and the motor run until a bag of corn 84 is in position underneath the high frequency electrode J. After this operation the switch 120 is opened.

In Figure 10 is illustrated a partially cutaway view of a cabinet 150 adapted to be employed for this apparatus. This cabinet is provided with a conventional coin chute 80 which has a mouth opening on the exterior of the cabinet and which extends into the interior. This coin chute is shown in more detail in Figures 1 and 4. Below the coin chute is the opening for egress of the popped corn and this is arranged so that the bags of popped corn slide down the lower panel thereof after being dumped off of the conveyor 81 upon the switch tripping member 92 which is directly above the bottom of the egress opening.

An embodiment of this invention has been set forth in detail in the foregoing specification and the attached drawing, however I do not desire to be limited to the details set forth except insofar as they are defined by the following claims.

I claim:

1. In apparatus of the class described, the combination of a high frequency current generator, spaced-apart electrode means connected to said generator for treating material to be processed with high frequency current and positioned therebetween, check actuated switch means for controlling the energization of said high frequency current generator for processing said material, switch means actuated by the material being processed after said material has been processed to the desired degree, and means controlled by said last mentioned switch means for discharging said material after processing.

2. In apparatus of the class described the combination of a high frequency current generator

for generating a high frequency field, a conveyor for carrying material to be processed with high frequency current into said high frequency field, means for moving said conveyor, control means for controlling the energization of said high frequency current generator for processing said material, said control means including a switch adapted to be closed by the expansion of the said material when said material has been processed to the desired degree to automatically de-energize selected circuits of said generator.

3. In apparatus of the class described the combination of a high frequency current generator for generating a high frequency field, a conveyor for carrying material to be processed with high frequency current into said high frequency field, means for moving said conveyor, control means for controlling the energization of said high frequency current generator for processing said material, said control means including a switch adapted to be closed by the expansion of the said material when said material has been processed to the desired degree, connections for energizing said motor when said switch is closed for discharging said processed material from said conveyor, and switch means automatically actuated when said material is processed to the desired degree to de-energize selected circuits of said generator.

4. In apparatus of the class described the combination of a high frequency current generator for generating a high frequency field, means for positioning material to be processed with high frequency current in said high frequency field, control means for controlling the energization of said high frequency current generator for processing said material, said control means including a switch adapted to be closed by the expansion of the said material when said material has been processed to the desired degree, connections for energizing said first mentioned means when said switch is closed to move said processed material out of said high frequency field, and switch means automatically actuated when said material is processed to the desired degree for de-energizing selected circuits of said generator.

5. In apparatus of the class described the combination of a high frequency current generator for generating a high frequency field, a conveyor for positioning popcorn to be popped in said high frequency field, a motor for driving said conveyor, control means for controlling the energization of said high frequency current generator for processing said popcorn until said popcorn has been popped, and switch means automatically actuated by the expansion of said popped corn for connecting said motor to a source of current supply whereby said popped corn is moved out of said high frequency field.

6. In apparatus of the class described the combination of a high frequency current generator for generating a high frequency field, a conveyor for carrying a bag of corn to be popped into said high frequency field, a motor for driving said conveyor, control means for controlling the energization of said high frequency current generator for processing said corn, and switch means automatically actuated by the expansion of the popped corn in said bag, connections between said switch, said motor and a source of current supply for energizing said motor when said switch is closed whereby said bag of popped corn is moved out of said high frequency field and a bag of unpopped corn is moved into position for the next popping cycle.

7. In apparatus of the class described the combination of a check controlled switch, a high frequency current generator for generating a high frequency field, means controlled by said switch for connecting selected circuits of said generator to a source of current supply, means for moving material to be processed with high frequency current into said high frequency field, control means for holding said check controlled switch closed and for controlling the energization of said high frequency current generator for processing said material, additional control means including a switch adapted to be closed when said material has been processed to the desired degree and connections to said additional control means for disabling said first mentioned control means when said additional control means is actuated.

8. In apparatus of the class described the combination of a check controlled switch, a high frequency current generator for generating a high frequency field, means controlled by said switch for connecting selected circuits of said generator to a source of current supply, means for moving material to be processed with high frequency current into said high frequency field, control means for holding said check controlled switch closed and for controlling the energization of said high frequency current generator for processing said material, additional control means including a switch adapted to be actuated when said material has been processed to the desired degree, connections to said additional control means for disabling said first mentioned control means when said additional control means is actuated and means for adjusting said last mentioned switch to control the degree of processing of said material.

9. In apparatus of the class described the combination of a check controlled switch, a high frequency current generator for generating a high frequency field, means controlled by said switch for connecting selected circuits of said generator to a source of current supply, means for moving material to be processed with high frequency current into said high frequency field, control means for holding said check controlled switch closed and for controlling the energization of said high frequency current generator for processing said material, additional control means including a switch adapted to be actuated by the expansion of said material being processed, connections to said additional control means for disabling said first mentioned control means when said additional control means is actuated and means for adjusting said last mentioned switch to control the degree of processing of said material.

10. In apparatus of the class described the combination of a check controlled switch, electromagnetic means for locking said switch in closed position, a high frequency current generator for generating a high frequency field, means controlled by said switch for connecting selected circuits of said generator to a source of current supply, means for holding material to be processed with high frequency current in said high frequency field, control means responsive to the processing of said material for controlling the energization of said high frequency current generator, said control means being connected to de-energized selected circuits of said generator and unlock said check controlled switch when said material has been processed to the desired degree, means controlled by said control means for moving said processed material out of said high frequency field, and means for de-energizing

ing said last mentioned means when said processed material is moved out of said high frequency field.

11. In apparatus of the class described the combination of a check controlled switch, electromagnetic means for locking said switch in closed position, a high frequency current generator for generating a high frequency field, means controlled by said switch for connecting selected circuits of said generator to a source of current supply, means for holding material to be processed with high frequency current in said high frequency field, control means responsive to the processing of said material for controlling the energization of said high frequency current generator, said control means being connected to de-energized selected circuits of said generator and unlock said check controlled switch when said material has been processed to the desired degree, means controlled by said control means for moving said processed material out of said high frequency field, and a switch for de-energizing said last mentioned means when said processed material is moved out of said high frequency field.

12. In apparatus of the class described the combination of a check controlled switch, electromagnetic means for locking said switch in closed position, a high frequency current generator for generating a high frequency field, means controlled by said switch for connecting selected circuits of said generator to a source of current supply, means for holding material to be processed with high frequency current in said high frequency field, control means including a switch responsive to the processing of said material for controlling the energization of said high frequency current generator, said control means being connected to de-energized selected circuits of said generator and unlock said check controlled

switch when said material has been processed to the desired degree, means controlled by said control means for moving said processed material out of said high frequency field, means for de-energizing said last mentioned means when said processed material is moved out of said high frequency field, and means for adjusting said last mentioned switch to control the degree of processing of said material.
